COMMEMORATIVE MEDALLION OR THE LIKE

Virgil M. Hanks, Jr., 89 San Pablo Ave.,
San Francisco, Calif.

Filed Mar. 7, 1969, Ser. No. 16,105

Term of patent 14 years

Int. Cl. D11—03

U.S. Cl. D29—19

FIG_1

FIG_2

FIG. 3

FIG. 4

FIG. 1 is a view of the obverse face of the commemorative medallion or the like embodying my new design;

FIG. 2 is a front edge view of the commemorative medallion shown in FIG. 1;

FIG. 3 is a view of the reverse face; and

FIG. 4 is a view in section taken along the line 4—4 of FIG. 3.

I claim:

The ornamental design for a commemorative medallion or the like, substantially as shown.
